ELECTRICAL CONTROL SYSTEM FOR PRESSES

Walter Ernst, Mount Gilead, Ohio, assignor to
The Hydraulic Development Corp. Inc., Wil-
mington, Del., a corporation of Delaware

Application August 31, 1939, Serial No. 292,931

8 Claims. (Cl. 60—52)

This invention relates to electrical control systems for hydraulic machinery, and especially for presses.

One object of this invention is to provide an electrical control system for hydraulic machinery, such as presses, wherein the control switch assembly is simplified so that the same electrical units perform the functions of selecting the circuits and of initiating the energization of the circuits.

Another object is to provide an electrical control system for presses, wherein the system is controlled by push-button switches which may be locked in either of two opposite positions so that a given push-button switch serves not only as a momentary-action switch but also as a selector switch, thereby providing a system wherein one switch performs the functions previously performed by two switches.

Another object is to provide an electrical control system for hydraulic machinery, such as presses, wherein the source of pressure fluid is controlled as to its delivery by an electrical device, such as a solenoid, the energization of which is under the control of a switch assembly wherein the functions of momentary starting and stopping switches are combined with the functions of selector switches so as to reduce the number of switches and circuits required, and thus to simplify the control system.

In the drawing:

Figure 1 is a perspective view in front elevation of a commercial form of press embodying the electrical control system of this invention.

Figure 2 is a wiring diagram showing the electrical control system of this invention.

Figure 3 is a diagrammatic view, partly in section, showing one form of combined push-button and selector switch.

In general, the electrical control system of this invention consists of a solenoid which controls the direction of distribution of pressure fluid to the press cylinders, this solenoid being under the control of a magnetic contactor. The magnetic contactor, in turn, is under the control of a plurality of switches, two of which are combined push-button and selector switches. One such combined switch serves as a starting switch for forward operation, and also as a selector switch for semi-automatic or full automatic operation. The other combined switch serves likewise as a push-button switch or as a selector switch for automatic operation or hand operation, in the latter instance rendering the electrical control system temporarily inoperative.

The combined switch itself is, in effect, a single-pole double-throw push-button switch, which normally rests in a neutral position between its two sets of poles, but which may be moved into engagement with the poles either momentarily or for a greater length of time by means of a locking device. This locking device locks the push-button switch in at least one of its two operating positions.

10 Referring to the drawing in detail, Figure 1 shows a hydraulic press embodying the electrical control system of this invention, and consists of a housing 10 containing a bed 11, only a portion of which is visible. Rising from the bed 11 are side members 12 forming housings concealing the strain rods 13, and push-back cylinders 14 having plungers 15 connected to the press platen 16 for returning the latter to its retracted position as shown in Figure 1. The platen 16 is connected to the main plunger 17, which reciprocates in the main cylinder 18, only the lower end of which is visible. The main cylinder 18 is mounted on the press head 19, which is connected to the upper ends of the strain rods 13 and to the press side member 12.

15 The press head 19 is surmounted by a fluid tank or surge tank 20 having a gauge 21 thereon for indicating the level of fluid in the tank. The press head 19 also is provided with a shelf 22 which serves to support a housing 23, within which are mounted the motor and pump for supplying pressure fluid to the main cylinder 18 and push-back cylinders 14. The lower housing 10 is provided with a closure or removable door 24, permitting access to be had to the parts concealed by the housing 10. A hand lever 25, mounted upon the shaft 26, provides for manual control of the press when the electrical control system is deenergized, or in the event of the failure thereof. The remaining electrical elements of Figure 1 are described below in connection with the wiring diagram.

20 The electrical system shown in Figure 2 consists of the electric motor 30, connected by the lines 31, 32 and 33 to the magnetic motor starting switch, generally designated 34, and consisting of an armature 35 carrying switch blades 36, 37 and 38 and provided with an energizing coil 40. The blades 36, 37 and 38 are connected, respectively, to the branch power lines 40a, 41 and 42 leading to the main power lines 43, 44 and 45, respectively. The switch blade 39 forms an interlock or holding switch for maintaining the energization of the coil 40 when the normally open motor starting push-button switch 47 is

released after being momentarily depressed to start the motor.

The push-button switch 47 is connected to the opposite poles of the switch blade 39 by the lines 48 and 49, respectively, the line 48 continuing to a junction with the branch power line 41. The coil 40 is connected at one end, by the line 50, to the branch power line 42 and at its other end, by the line 51, to one pole of the normally closed motor stop push-button switch 52, the opposite end of which is connected to an extension of the line 49 beyond the normally open motor starting push-button switch 47. In this manner the starting and stopping of the pump-operating motor 30 are under the control of the two push-button switches 47 and 52.

The distribution of pressure fluid from the pump to the main cylinder 18 and push-back cylinders 14 is under the control of a solenoid 53. The latter may either shift a reversing valve, as in an open circuit, or reverse the shift ring of a reversible variable delivery pump, as in a closed circuit. In either case the energization of the solenoid 53 is under the control of the magnetic contactor, generally designated 54, and having a winding or operating coil 55, an armature 56 and switch blades 57, 58 and 59. The switch blades 57 and 58 directly control the energization of the solenoid 53 from the branch power lines 60 and 61, whereas the switch blade 59 forms an interlock or holding circuit to maintain the energization of the operating coil 55, in the manner described below.

The energization of the contactor 54 is under the control of the combined push-button and selector switches 62 and 63, and also under the control of the tonnage control limit switch 64, the oil temperature limit switch 65, the platen-operated auxiliary start limit switch 66 and the forward push-button switch 67. The tonnage control switch 64 is a normally closed spring-loaded switch having a pressure plunger which at a predetermined pressure overcomes the thrust of the spring and opens the switch to break the circuit. The oil temperature limit switch 65 is a normally closed switch, actuated by a thermostat at a predetermined temperature to stop automatic operation when the oil temperature reaches a maximum limit. The platen-operated auxiliary start limit switch 66 is a normally open limit switch which is automatically closed when the platen nears the end of its return stroke so as to automatically restart the platen upon another forward stroke, and thereby to effect full automatic operation. The forward push-button switch 67 is merely an additional precaution to require the use of the other hand of the operator which is not required in manipulating the push-button switch 62 for safety purposes.

The switches 62 to 67 are interconnected by an electrical circuit with the magnetic contactor 54. A "semi-automatic" pole of the switch 62 is connected by the line 68 to a pole of the forward push-button switch 67, from the opposite pole of which the line 69 runs to one pole of the limit switch 66. From the opposite pole of the latter the line 70 runs to a "full automatic" pole of the switch 62. The other "semi-automatic" pole and "full automatic" pole are interconnected by the line 71, which continues onward to one pole of the tonnage control switch 64. From the same pole the line 72 runs to one end of the operating coil 55 of the magnetic contactor 54, the other end of which is connected by the

line 13 to an "automatic" pole of the push-button switch 63, the remaining "automatic" pole of which is connected by the line 74 to one pole of the oil temperature limit switch 65, the other pole of which is connected by the line 75 to the branch power line 61. The remaining pole of the tonnage control switch or pressure-responsive switch 64 is connected by the line 76 to one pole of the interlock blade 59 of the magnetic contactor 54, the opposite pole of which is connected by the line 77 to the branch power line 60, and by the line 78 to one pole of the forward push-button switch 67.

In order to indicate when the automatic circuit is in operation, there is provided a pilot light 79, connected on the one side by the line 80 to one pole of the switch 63 and on the other side by the line 81 to one pole of the magnetic contactor interlock blade 59. The line 81 optionally contains a resistance 82, depending upon the characteristics of the pilot light 79.

The combined push-button and selector switches 62 and 63 may be of any suitable type, one type being indicated diagrammatically in Figure 3. This switch consists of a plunger 83 carrying a push-button 84 and a switch blade 85, with contact points 86. The plunger 83 is also provided with a collar 87 engaged by a coil spring 88, which abuts against the rear switch housing wall 89. Surrounding the plunger 83 is a rotatable sleeve 90 of approximately cylindrical form, having an annular portion 91 projecting from the front panel of the switch housing 89 and having a grooved portion 92 loosely engaging the latter. The annular portion 91 is preferably knurled so as to be easily engageable by the fingers of the operator.

Connected to the sleeve 90, as by the bolts 93, is a cylindrical cam 94 having a cam surface 95 engaging a pin 96 mounted upon the plunger 83. Mounted adjacent the raised position of the switch blade 85 are spaced pairs of switch poles 97 and 98, respectively. By pushing the push-button 84 the switch blade 85 may be caused to engage the poles 98, whereas a motion of the plunger 83 in the opposite direction causes the switch blade 85 to engage the poles 97 when the sleeve 90 is so rotated that the pin 96 engages the lower portion of the cam surface 95. The switch blade 85 may be locked midway between the contact points 97, 97 and 98, 98 by rotating the annular portion 91 with the sleeve 90 so that the pin 96 rides up onto the high part of the cam 94.

In the operation of the circuit shown in Figure 2, the motor 30 is started by momentarily depressing the motor starting push-button switch 47. This energizes the operating coil 40 of the magnetic contactor 34, and the energization is maintained by a holding circuit established through the line 49, the interlock switch blade 39 and the line 41. These bridge the push-button switch 47 when it is released. The motor may be stopped at any time by depressing the normally closed push-button switch 52, thereby halting the pump which supplies pressure fluid to the main cylinder 18 and push-back cylinders 14.

If the operator decides to employ hand-operation by using the hand lever 25, he depresses the combined push-button and selector switch 63 and locks it by rotating the annular portion 91 so that the circuit is broken between the lines 73 and 74. The electrical control circuit is then deenergized and the press is controlled directly

by means of the hand lever 25, thereby directly moving the control rod of the press and the main control valve, or the pump shift ring, as the case may be. To change from hand operation to semi-automatic operation, the switch 63 is returned to its upper "automatic operation" position, and the operator then depresses the forward starting push-button 67, and moves the combined push-button 62 until it engages the "semi-automatic" contacts. If he desires semi-automatic operation, whereby the platen 16 executes a forward stroke, halts, executes a return stroke and then halts at the end of its return stroke, no further attention is required on the part of the operator.

The depressing of the switches 62 and 67 energizes the operating coil 55 of the magnetic contactor 54 by way of the branch power line 61, the line 75, the oil temperature limit switch 65, the line 74, the combined push-button and selector switch 63, the line 73, the operating coil 55, the line 72, the line 71, the combined push button and selector switch 62, the line 68, the forward push-button 67 and the lines 78 and 77, to the branch power line 60.

The releasing of push-button switches 62 and 67 does not deenergize the magnetic contactor 54 because the closing of the switch blades 57, 58 and 69 operates a holding circuit through the switch blade 59. Thus the operating coil 55 is now energized by way of the line 75, the oil temperature limit switch 65, line 74, combined push-button and selector switch 63, line 73, operating coil 55, line 72, tonnage control limit switch 64, line 76, switch blade 59 and line 77, to the branch power line 60. The solenoid 53 is then directly energized through the switch blades 57 and 58, and operates upon the main control valve or the pump shift ring to deliver pressure fluid to the top of the main cylinder 18, and bring about a forward stroke of the main plunger 17 and platen 16.

When the platen 16 has advanced and performed work upon the workpiece, the consequent rise in pressure opens the tonnage control switch 64 when its set pressure is exceeded. This breaks the energization circuit of the magnetic contactor coil 55 between the lines 72 and 76 and causes the magnetic contactor 54 to open, thereby deenergizing the solenoid 53. The usual springs will then return the main control valve or pump shift ring to the reversed delivery position so that pressure fluid is supplied to the push-back cylinders 14 and withdrawn from the main cylinder 18. Under these circumstances the main plunger 17 and platen 16 will execute a return stroke. In a mechanical manner not shown in the drawing but known to those skilled in the art, the platen 16, at the end of its return stroke, directly shifts the main valve or shift ring of the pump to a neutral position, whereby no further pressure fluid is delivered either to the push-back cylinders 14 or main cylinder 18. The main platen 16, therefore, halts automatically at the end of its return stroke and completes one cycle of semi-automatic operation.

If full automatic operation is desired, whereby the press platen 16 will perform a repeated number of forward and return strokes without halting more than momentarily at the end of each stroke, the operator depresses the push-button switches 62 and 67 as before to get the device started and then actuates the locking ring or annular portion 91 to bring the switch blade 85 to its dotted position designated "full auto-

matic," namely, the upper position in Figure 2. The magnetic contactor 54 and solenoid 53 are energized, as follows: From the branch line 61 current flows through the line 75, the oil temperature limit switch 65, the line 74, switch 63, and line 73 to the operating coil 55. From here the current flows through lines 72, 71 and 70, the switch 66, lines 69, 78, 77 and 60 back through the line 64. As soon as the coil 55 is energized, the blades 59, 58 and 57 form the circuits previously described in connection with semi-automatic operation, switch 66 being bridged by the lines 60 and 77, blade 59, line 76 and switch 68. Consequently the platen 16 executes a working stroke, is reversed automatically by the opening of the tonnage control pressure-responsive switch 64, and returns to its starting position. Instead of remaining at the end of its return stroke, as in semi-automatic operation, however, the platen 16 closes the switch 66 before it moves the pump control or main valve to neutral. The closing of the limit switch 66 in this manner bridges the forward push-button switch 67 and effects starting energization between the lines 71 and 70 by way of the lines 69 and 70 and the now closed limit switch 66. Under these circumstances, the magnetic contactor coil 55 is automatically reenergized and the consequent reenergization of the solenoid 53 again shifts the main valve or pump control to cause pressure fluid to be applied to the top of the main cylinder 18. Accordingly, the press platen 16 immediately starts upon another forward or working stroke without halting more than momentarily at the end of its previous return stroke. The press will then proceed to execute a repeated number of cycles until the switch 62 is released from its full automatic position, or until the oil temperature limit switch 65 is opened by a serious rise in temperature, or the motor stop push-button switch 52 is operated, or until the operator depresses the switch 63.

Thus, in the control circuit of the present invention, the combined push-button and selector switches 62 and 63 not only serve the functions of the ordinary push-button switches previously employed, but also serve to select the circuit for hand or automatic operation, and also for full automatic or semi-automatic operation. Thus, by the present invention, two push-button switches previously considered necessary have been eliminated, namely, an additional forward push-button switch similar to the forward push-button switch 67, and a normally closed reverse push-button switch similar to the motor stop push-button switch 52. Obviously, the operation of the entire circuit may be halted at any time by opening the motor stop switch 52.

It will be understood that I desire to comprehend within the invention such modifications as come within the scope of the claims.

Having thus fully described the invention, what I claim as new and desire to secure by Letters Patent, is:

1. In a hydraulic press control system, the combination with a reversible hydraulic motor means having a reciprocable ram and a source of pressure fluid therefor with a flow-control member for reversibly controlling the distribution of pressure fluid to said hydraulic motor means, of an electric circuit comprising means including an electrical device for selectively shifting said flow-control member to ram-advancing and retracting positions, limit switch means for automatically altering the energization of said electrical

device for initiating a retraction stroke of said ram at the end of a ram-advancing stroke, means for automatically re-altering the energization of said electrical device at the end of a retraction stroke for effecting an immediately repeated advancing stroke, a combined main starter and selector switch for effecting energization of said circuit and for selecting said immediately repeated advancing stroke, an auxiliary starter switch adapted to cooperate with said main starter and selector switch for starting energization of said circuit, and means for electrically connecting said last mentioned switch selectively with said auxiliary starter switch or said re-altering means.

2. In a hydraulic press control system, the combination with reversible hydraulic motor means having a reciprocable ram and a source of pressure fluid therefor with a flow-control member for reversibly controlling the distribution of pressure fluid to said hydraulic motor means, of an electrical control circuit arranged to effect full automatic reversal of said flow-control member at the end of the advancing and retracting strokes of said ram, said circuit including a combined starter and selector switch movable selectively from a neutral position into one of two operative positions, circuit means adapted to be closed by said combined switch in one of its operative positions for starting operation of said hydraulic motor and conditioning the same for semi-automatic operation, and circuit means adapted to be closed by said combined switch in its other operative position in cooperation with means operable at the end of a retraction stroke of said motor.

3. In a hydraulic press control system, the combination with reversible hydraulic motor means having a reciprocable ram and a source of pressure fluid therefor with a flow-control member for reversibly controlling the distribution of pressure fluid to said hydraulic motor means, of an electrical control circuit arranged to effect full automatic reversal of said flow-control member at the end of the advancing and retracting strokes of said ram, said circuit including combined momentary and prolonged contact switch means for selectively effecting full automatic and semi-automatic energization of said circuit to selectively produce full automatic and semi-automatic operation of said ram respectively, said switch means including a push-button switch having a device for holding the same in a prolonged contact position.

4. In a hydraulic press control system, the combination with reversible hydraulic motor means having a reciprocable ram and a source of pressure fluid therefor with a flow-control member for reversibly controlling the distribution of pressure fluid to said hydraulic motor means, of an electrical control circuit arranged to effect full automatic reversal of said flow-control member at the end of the advancing and retracting strokes of said ram, said circuit including combined momentary and prolonged contact switch means for selectively effecting full automatic and semi-automatic energization of said circuit to selectively produce full automatic and semi-automatic operation of said ram respectively, said switch means including a push-button switch having selective holding means engageable there-

with for releasably holding said switch in a prolonged contact position.

5. In a hydraulic press control system, the combination with reversible hydraulic motor means having a reciprocable ram and a source of pressure fluid therefor with a flow-control member for reversibly controlling the distribution of pressure fluid to said hydraulic motor means, of an electrical control circuit arranged to effect full automatic reversal of said flow-control member at the end of the advancing and retracting strokes of said ram, said circuit including combined momentary and prolonged contact switch means for selectively effecting full automatic and semi-automatic energization of said circuit to selectively produce full automatic and semi-automatic operation of said ram respectively, said switch means including a push-button switch movable selectively into one of two contact-engaging positions and having holding means for releasably holding said switch in a prolonged contact in one of said contact-engaging positions.

6. In a hydraulic press control system, the combination with hydraulic motor means having a reciprocable ram and a source of pressure fluid with a flow-control member for reversibly controlling the distribution of pressure fluid to said hydraulic motor means, of an electrical control circuit arranged to selectively effect full automatic and semi-automatic operation of said flow-control member for producing full automatic and semi-automatic operation of said ram, said electrical circuit including a combined push-button and selector switch momentarily engageable and having a holding device for holding said switch in prolonged contact.

7. In a hydraulic press control system, the combination with hydraulic motor means having a reciprocable ram and a source of pressure fluid with a flow-control member for reversibly controlling the distribution of pressure fluid to said hydraulic motor means, of an electrical control circuit arranged to selectively effect full automatic and semi-automatic operation of said flow-control member for producing full automatic and semi-automatic operation of said ram, said electrical circuit including a combined push-button and selector switch momentarily engageable and having a holding device for holding said switch in prolonged contact, said switch having a neutral position of disengagement.

8. In a hydraulic press control system, the combination with hydraulic motor means having a reciprocable ram and a source of pressure fluid with a flow-control member for reversibly controlling the distribution of pressure fluid to said hydraulic motor means, of an electrical control circuit arranged to selectively effect full automatic and semi-automatic operation of said flow-control member for producing full automatic and semi-automatic operation of said ram, said electrical circuit including a combined push-button and selector switch momentarily engageable and having a holding device for holding said switch in prolonged contact, said switch having a semi-automatic position of engagement, a full-automatic position of engagement and a neutral position of disengagement therebetween.
